Inventor:

Charles C. Blake

UNITED STATES PATENT OFFICE.

CHARLES C. BLAKE, OF BROOKLINE, MASSACHUSETTS.

WIRING-TACK.

1,017,036.

Specification of Letters Patent. Patented Feb. 13, 1912.

Application filed September 18, 1911. Serial No. 650,005.

To all whom it may concern:

Be it known that I, CHARLES C. BLAKE, residing at Brookline, in the county of Norfolk and State of Massachusetts, have invented certain Improvements in Wiring-Tacks, of which the following is a specification.

The present invention relates to means for supporting insulated wires in position on wood surfaces or plastered walls, in such manner as to hold the same securely without marring or damaging the wood or plaster and also present an attractive appearance.

The invention consists of a wiring tack adapted to embrace the insulated conductors of a pair, and consists of a metal plate having an insulating lining and a nail or pin passing through the central part of the plate and lining, the parts being held together by frictional pressure or with a suitable cement, all of which I will now proceed to describe and point out in particular in the appended claims.

In the drawings which form a part of and illustrate the invention,—Figure 1 is a perspective view of the insulated wiring staple; Figs. 2 and 3 are respectively top and side views of the metal plate; Figs. 4 and 5 are respectively a top and side view of the insulating lining; Fig. 6 is a section on line x, x of Fig. 5 looking in the direction of the arrow; Fig. 7 is a detached view of the nail or pin; Fig. 8 is a view to illustrate the application of the staple; and Fig. 9 is a sectional view illustrating a modification.

In the drawings, a is an oblong metal plate having its ends 1, 1 bent at substantially right angles; the central portion of the top part is elevated to form a ring-shaped projection 2, which has a central depression 3 whose edges are drawn out thin forming a tubular orifice. The plate is formed in dies and is thus very cheaply made. Within the plate a is an insulated lining b made from a ribbon of fiber or other suitable material, while soft and easily worked in a mold, having its central portion folded or doubled over so that the sides touch or nearly so, as 5, then turned over to form the tops, 9, 9, and again to form the sides 4, 4, and a pin forced between the sides, centrally thereof to make a hole 7; at the same time the fiber is pressed outward in each side making a semi-circular wall 6. The contour of the lining b is such that it

fits snugly inside the plate a , and when the nail or pin c is inserted into the depression 3 and pressed downward through the straight hole 7, the parts are held together; the head of the nail rests in the depression 60 3 and is held by its lower edges and also by the walls 6 of the central portion 5, of the lining b which steadies the same.

By reference to Fig. 8, in which is shown a wire tack securing the conductors C, C of 65 a pair to a support S, it will be seen that the lining b prevents any contact between the metal parts of the tack and the conductors. I may, if I choose, cause the plate and lining to adhere to each other by means of interposed cement or sticky substance.

It is not strictly essential that the elevated portion 2 be formed on the upper face of the plate, although it gives stability to the same in driving the nail, and Fig. 9 shows a cross-section of a device in which the elevation 2 is left off, in this case the depression 3 may extend farther inward to give support to the nail head.

The several parts may be kept in separate 80 places and assembled when about to be used, but I prefer to assemble the parts and pack the completed tacks in boxes for sale.

I claim as my invention—

1. A wiring tack comprising a metal plate 85 having its ends bent over and downward with a central opening through the metal, a nail or pin having its head supported in said opening, and an insulating lining covering the interior surface of the plate the 90 central portion of which is doubled, perforated and extending downward forming a midway partition and embracing the nail or pin, as set forth.

2. A wiring tack comprising a metal plate 95 having opposite ends bent at substantially right angles with a central depression in its upper portion extending through the metal forming a tubular orifice, a nail or pin supported by its upper end in said depression, 100 and an insulating lining the central portion of which is doubled and centrally perforated, its sides being parallel and embracing the nail or pin.

3. A wiring tack comprising a metal plate 105 having its ends bent over and downward and a portion of its upper surface elevated with a central depression extending through the metal, a nail or pin having its head supported in said depression, and an insulating lin- 110

ing the central portion of which is doubled and perforated and embraces the nail or pin, as set forth.

4. A wiring tack comprising an oblong metal plate having its ends bent over and downward, a portion of its upper surface being elevated and having a central depression extending through the metal, a nail or pin supported by its upper end in said depression, and an insulating lining the central portion of which is doubled and perforated, its sides being parallel and embracing the nail or pin.

5. A wiring tack comprising a metal plate having opposite ends bent at substantially right angles, a portion of its upper surface

having a ring-shaped elevation with a central depression extending through the metal, a nail or pin supported by its upper end in said depression, and an insulating lining the central portion of which is doubled and centrally perforated with its sides parallel and embracing the nail or pin.

In testimony whereof, I have signed my name to this specification in the presence of two subscribing witnesses, this fourteenth day of September 1911.

CHARLES C. BLAKE.
